BOILER

Edward S. Cornell, Jr., Larchmont, N. Y., assignor, by mesne assignments, to American Radiator & Standard Sanitary Corporation, New York, N. Y., a corporation of Delaware

Application August 13, 1936, Serial No. 95,753

15 Claims. (Cl. 122—225)

My invention relates to improvements in heating apparatus, and the same has for its object to provide a boiler for use in connection with heating systems, and more particularly of the type designed to burn liquid or gaseous fuel.

Further, said invention has for its object to provide a boiler in which all of its operating parts including the apparatus for burning liquid or gaseous fuel as well as the means for insuring the rapid circulation of the water may be completely housed within an outer casing or jacket.

Further, said invention has for its object to provide a boiler presenting a proportionately large heat absorbing surface to the burning or radiant fuel, and the hot gases and products of combustion produced thereby.

Further, said invention has for its object to provide a boiler having a large combustion chamber, and affording a long flue travel for the hot gases and products of combustion in their passage from the combustion chamber to the smoke outlet.

Further, said invention has for its object to provide a boiler in which a large area of the interior portions, which in effect constitute an extended crown sheet, is exposed directly to the burning fuel and the hot gases and products of combustion at the time that the same are produced or liberated.

Further, said invention has for its object to provide a boiler of the sectional type having a large combustion chamber and a water backed member extending across the same exposed on all sides to the radiant heat of the fuel and lying directly in the path of the hot gases and products of combustion in order to permit the greatest absorption of heat thereby.

Further, said invention has for its object to provide a boiler in which the flow of water may be greatly accelerated and more efficiently circulated.

Other objects will in part be obvious and in part be pointed out hereinafter.

To the attainment of the aforesaid objects and ends my invention consists in the novel features of construction, and in the combination, connection and arrangement of parts herein-after more fully described and then pointed out in the claims.

In the accompanying drawings—

Figure 1 is a side elevation showing one form of boiler constructed according to and embodying my said invention, the same being shown with the jacket or casing removed;

Fig. 2 is a front end view;

Fig. 3 is a rear end view;

Fig. 4 is a central longitudinal section;

Fig. 5 is a transverse section essentially on the line 5—5 of Fig. 4;

Fig. 6 is a detail longitudinal section on the line 6—6 of Fig. 5;

Fig. 7 is a horizontal section on the line 7—7 of Fig. 4, and

Figs. 8 and 9 are respectively elevational and sectional views showing the lower ends of the jacket members and the means for securing the parts together.

In said drawings 10 designates the boiler as a whole which is of substantially rectangular outline and composed of a plurality of transverse sections including a deep front section 11, a deep back section 12, and one or more relatively shallow intermediate sections as 13, 13', each having a continuous peripheral water-way forming the top, side walls and bottom of the boiler. The said sections are communicatively connected at their upper, central portions by large nipples 15, and when the boiler includes more than one intermediate section the front section 11 and the adjacent intermediate section 13' are provided upon their outer sides near their middle portions with registering hubs or projections 16' within which are secured nipples 16. At their opposite lower corners the several sections are connected by smaller nipples 16. The operative parts of the boiler may be enclosed by a suitable sheet metal jacket 10a, hereinafter described.

The front section 11 has the front wall of its lower portion carried horizontally inwardly at 11a and thence downwardly and inwardly to form an inclined wall portion 11b whose lower end meets the upper end of a vertical wall portion 11c of the adjacent intermediate section 13', which terminates in a short, inwardly extending base portion 11d. The sides of the front section 11, at its set-back lower end, are provided with open-work frame members 11s, and within said set-back portion, which constitutes a chamber, is disposed an oil burner 40a, of the gun type, whose discharge nozzle 41 extends through an opening 42 in the vertical wall portion 11c. The upper end of said front section is carried horizontally inwardly to form the top portion 11e.

The front section 11 is provided at its inner, upper portion with a hollow, horizontal crown sheet member 11f which is connected to and communicates at its opposite ends with the water spaces of the side wall members of said front section 11, and at its intermediate portion said

crown sheet member 11^f is communicatively connected with the lower ends of hollow, vertical wall portions 11^g whose upper ends are similarly connected to and communicate with the water space of the top 11^e .

The intermediate sections 13 , $13'$ are provided with registering crown sheet members 13^2 , $13^2'$ which depend from and communicate with hollow, vertical wall portions 13^3 , $13^3'$. The said vertical wall portions 13^3 , $13^3'$ communicate at their upper ends with the water space of the top 11^e , and register with the vertical wall portion 11^g of the front section 11 , and with the inner end of the inwardly extending member 12^h of the back section 12 . The said wall portions 11^g , 13^3 jointly form three parallel, horizontal flues 20 extending from the combustion chamber to the smoke outlet.

From the crown sheet members of the intermediate sections 13 , $13'$ depend hollow, vertical wall portions 11^m , whose lower ends terminate in hollow partition members 11^k , which register with each other, and form a horizontal, water-backed partition which is disposed in substantially the same horizontal plane as the horizontal portion 11^a of the front wall. The front edge of the partition member 11^k of the intermediate section $13'$ is preferably tapered. The said partition members 11^k communicate at their opposite ends with the water-backed side wall members of the intermediate sections 13 , $13'$, and midway between their said ends said partition members 11^k communicate with the lower ends of the hollow, vertical wall portions 11^m , which latter have their upper ends connected to and communicate with the crown sheet members 11^f .

The bottom 11^d , top 11^e , crown sheet members 11^f , and partition members 11^k all have their registering, contracting edges disposed in vertical planes.

The front section is provided with clean-out openings 11^o having doors or closures 11^p which may be faced on their inner surfaces with refractory linings 11^r .

The back section 12 has a relatively deep lower portion 12^a , and a set back upper portion forming a shallow smoke-hood 12^b , having a collar 12^c to receive one end of a smoke pipe. The smoke-hood 12^b is coextensive in width with the width 50 of the boiler, and communicates with the rear or outlet ends of the flues. At its opposite ends the smoke-hood is provided with check-draft openings controlled by closures or damper 12^e . The back section 12 has an inwardly extending water-backed portion 12^f which merges intermediate the side walls of the boiler with a short horizontal inwardly extending portion 12^g whose inner edge registers with the rear edge of the crown sheet member 13^2 of the intermediate section 13 . The said inwardly extending portion 12^g is provided with hollow vertical wall members 12^h which communicate at their lower ends with the interior of the hollow transverse member connecting the side portions, and at their upper ends 65 with the water-backed top member 12^i of the section, and together with the corresponding member 13^3 of the intermediate section $13'$ and back section 12 form three parallel horizontal flues 20 leading from the combustion chamber to 70 the smoke outlet 12^b . The result of this arrangement is the formation of a fire-pot and combustion chamber of relatively large cubical content tapering towards its outlet end where it merges with the flues leading to the smoke outlet, and 75 results further in the production of a combustion

chamber having its top wall disposed in several horizontal levels.

The back section is provided at its lower portion with a clean out opening 21 provided with a closure 22 which is provided with a lining of refractory material 23 , and the base of the fire-pot and combustion chamber may be provided with a similar lining 24 .

The back section 12 is provided at its sides with supplemental water-ways comprising integrally 10 cast hollow vertical members 25 , 25^a which merge at the lower ends with hollow horizontal distributing members 26 formed partly on each boiler section and communicatively connected by nipples 26 . The inner sides of said distributing 15 members 26 have apertures 28 opening into the water-backed members constituting the base of the boiler. To the upper end of the vertical member 25 is connected, by a pipe 30 , an electrically operated distributing pump 31 which is 20 connected at its intake side with the return pipe 32 extending from the heating system. A branch pipe 32^b connects the return pipe 32 with the return inlet at the base of the boiler, and a three-way valve 32^c is provided at the junction 25 of the return pipe 32 with the branch pipe 32^b to cut out the distributing pump 31 and permit of the water from the heating system to be returned by gravity directly to the boiler.

To the upper end of the vertical member 25^a is connected, by a pipe 33 , the outlet side of domestic hot water heater 33^a , whose intake side is connected by a pipe 34 to the upper part of the water space of the boiler section. A flow pipe 36 , communicating with a source of water 35 , supply, is connected to the intake end of the coil 33^b of the hot water heater 33^a , and the outlet end of said coil 33^b may be connected by a pipe 35 with a hot water storage tank, or directly with the hot water supply system of the building.

The sheet metal jacket 10^a comprises essentially three parts, viz: a front member 40 which is conformed substantially to the contour of the front section 11 of the boiler, a back member 41 which is conformed substantially to the back section 12 of the boiler, and an intermediate or bridging section 42 of such width as may be necessary to cover the gap between the inner opposing edges of the front member 40 and the back member 41 of the jacket. The said sections 40 and 41 are provided on both sides adjacent their lower edges with longitudinal ribs 43 forming grooves upon the inner sides of said jacket members, and the intermediate section is provided with a similar rib 43^a whose inner surface is conformed to the outer surfaces of said ribs 43 . In said grooves are loosely fitted conforming curved plates 44 to the central portion of each of which is fixed a screw-threaded bolt 44^a which extends through an aperture in the grooved portion 43^a of the intermediate or bridging section 42 , and is provided with a nut whereby the several parts may be held secured to adjusted position.

The front jacket member 40 is provided with openings 45 , 46 having closures 45^a , 46^a to give access to the front section of the boiler and the openings therein, and the back jacket member 41 is provided with openings 47 , 48 having closures 47^a , 48^a , giving access to the rear section 12 of the boiler and the openings therein.

When desired the inner sides of the jacket members may be provided throughout with insulating lining 49 , as indicated at Figs. 4 and 5.

Having thus described my said invention, what I claim and desire to secure by Letters Patent is:

1. A boiler of the character described comprising a front section having an upper portion including a rearwardly extending lower wall intermediate of the section forming a burner chamber therebelow, a back section having a projecting lower portion, and an intermediate transverse section enclosing a fire pot and a combustion chamber, said back section having a smoke outlet therein, flues extending from said fire pot and combustion chamber to said smoke outlet, a water-backed crown sheet separating said fire pot and combustion chamber from said flues, and certain of said sections including registering transverse water-backed portions forming a partition in said fire pot and combustion chamber below said crown sheet, said crown sheet and said partition communicating at their opposite ends with the water-backed side wall portions of said sections, and said partition serving to direct the flow of hot gases and products of combustion over and under said partition before said currents pass out of said fire pot and combustion chamber.
2. A boiler of the character described comprising a front section having an upper portion including a rearwardly extending lower wall intermediate of the section forming a burner chamber therebelow, a back section having a projecting lower portion, and intermediate transverse sections enclosing a fire pot and a combustion chamber, a smoke outlet in said back section, and flues extending from said fire pot and combustion chamber to said smoke outlet, said sections having registering, transverse water-backed members forming the crown sheet separating said fire pot and combustion chamber from said flues, registering and transverse water-backed members forming a horizontal partition in said fire pot and combustion chamber below said crown sheet, said crown sheet and said partition communicating at their opposite ends with the water-backed side wall portions of said sections, and registering vertical water-backed members connecting said partition and crown sheet and forming longitudinal flues therebetween communicating at their forward and rear ends with said fire pot and combustion chamber, and said partition and said last named flues serving to divide the flow of hot gases and products of combustion into two currents passing over and under said partition and to cause said currents to combine again before the same pass out of said fire pot and combustion chamber.
3. A boiler of the character described comprising a front section, a back section having a smoke outlet therein, and intermediate transverse sections enclosing a fire pot and a combustion chamber, and flues extending from said fire pot and combustion chamber to said smoke outlet, means communicatively connecting the sections, and supplemental water ways each including a vertical member formed integrally with one of said sections, and horizontal members communicating at one end with said vertical member, said horizontal members being disposed at the lower ends of the several sections and communicatively connected with each other and having apertures therein communicating with the water spaces of said sections, and means associated with the boiler and communicating with the water ways thereof for forcibly circulating the water through said water ways and the sections.
4. A boiler of the character described comprising a front section, a back section having a smoke outlet therein and intermediate trans-
- verse sections enclosing a fire pot and a combustion chamber, and flues extending from said fire pot and combustion chamber to said smoke outlet, means communicatively connecting the sections, supplemental water ways each including a vertical member formed integrally with one of said sections, and horizontal members communicating with said vertical members, said horizontal members being disposed at the lower ends of the several sections and communicatively connected with each other and the water spaces of said sections, and a circulating pump associated with one of said vertical members for circulating the water through the apparatus.
5. A boiler of the character described having a rear lower portion extending rearwardly beyond the rear upper portion and enclosing one end of the fuel receptacle and combustion chamber, and an upper forward portion extending forwardly beyond the lower portion of the boiler end enclosing the opposite end of the fuel receptacle and combustion chamber and providing recesses within the geometrical outlines of the boiler to receive respectively, the boiler accessories, and a fluid fuel burner, said forward recess having its rear wall disposed in a vertical plane inwardly of the front of the boiler, and means in said rear wall for receiving the nozzle of the oil burner located in said recess.
6. A boiler of the character described having a rear lower portion extending rearwardly beyond the rear upper portion and enclosing one end of the fuel receptacle and combustion chamber, and an upper forward portion extending forwardly beyond the lower portion of the boiler and enclosing the opposite end of the fuel receptacle and combustion chamber and providing recesses within the geometrical outlines of the boiler to receive respectively, the boiler accessories, and a fluid fuel burner, said forward recess having its rear wall disposed in a vertical plane inwardly of the front of the boiler, means in said rear wall for receiving the nozzle of the oil burner located in said recess, and a jacket enclosing the boiler.
7. A boiler of the character described including front, back and intermediate sections, said back section having a lower portion extending rearwardly beyond the upper portion thereof and enclosing one end of the fuel receptacle and combustion chamber, and said front section having an upper portion extending forwardly beyond the lower portion thereof and enclosing the opposite end of the fuel receptacle and combustion chamber and providing a recess below the same to receive a fluid fuel burner; the lower front wall portion of the intermediate section adjacent said front section forming the rear wall of said recess, and means in said rear wall for receiving the nozzle of the fluid fuel burner located in said recess.
8. A boiler of the character described including front, back and intermediate sections, said back section having a lower portion extending beyond the upper portion thereof and enclosing one end of the fuel receptacle and combustion chamber, and said front section having an upper portion extending forwardly beyond the lower portion thereof and enclosing the opposite end of the fuel receptacle and combustion chamber and providing a recess to receive a fluid fuel burner; the bottom wall portion of said front section extending rearwardly and downwardly and meeting with the front wall portion of the intermediate section adjoining said front sec-

tion and jointly forming the top and rear walls of said recess, and means in said wall for receiving the nozzle of the fluid fuel burner located in said recess.

- 5 9. A boiler of the character described including front, back and intermediate sections, said back section having a lower portion extending rearwardly beyond the upper portion thereof and enclosing one end of the fuel receptacle and 10 combustion chamber, and said front section having an upper portion extending forwardly beyond the lower portion thereof and enclosing the opposite end of the fuel receptacle and combustion chamber and providing recesses within the 15 geometrical outlines of the boiler, respectively, to receive the boiler accessories, and a fluid fuel burner; the lower front wall portion of the intermediate section adjoining said front section forming the rear wall of said burner recess, and 20 means in said rear wall for receiving the nozzle of the fluid fuel burner located in said recess, said boiler accessories and said fuel burner lying wholly within the geometrical outlines of the boiler, and a metallic jacket enclosing the boiler.
- 25 10. A boiler of the character described comprising a front section having a water-backed upper portion including a rearwardly extending lower wall providing a burner chamber therebelow, a water-backed back section including a 30 rearwardly projecting lower portion and a water-backed intermediate section, the lower portions of said intermediate section and said back section enclosing a fire pot and combustion chamber, and the upper portion of said several sections enclosing flues communicating through said front section with said fire pot and combustion chamber, a water-backed crown sheet separating said fire pot and combustion chamber from said flues, and a transverse water-backed partition 35 on said intermediate sections in spaced relation to and below said crown sheet.

11. A boiler of the character described comprising front, back and intermediate transverse sections, said back section including a rearwardly projecting lower portion, and said front section including a forwardly projecting upper portion, the lower portions of said intermediate and back sections enclosing a fire pot and combustion chamber, and the upper portion of said several sections enclosing flues communicating through said projecting front portion with said fire pot and combustion chamber, a water-backed crown sheet separating said fire pot and combustion chamber from said flues, and a transverse water-backed partition on the intermediate of 55 said sections in spaced relation to and below said crown sheet within said fire pot and combustion chamber for directing the hot gases and products of combustion over and under the same through said projecting front portion into said flues.

12. A boiler of the character described comprising a water-backed enclosure including lower and upper portions, and a smoke outlet in said upper portion, said lower portion projecting beyond said upper portion at the rear and enclosing a fire pot and combustion chamber, and said upper portion projecting beyond said lower portion at the front and enclosing flues extending 65 from said fire pot and combustion chamber at

the front thereof to the smoke outlet, a water-backed crown sheet separating said fire pot and combustion chamber from said flues, and a transverse water-backed partition in said fire pot and combustion chamber below said crown sheet serving to direct the flow of hot gases and products of combustion from the combustion chamber over and under said partition into the flues through said projecting front portion. 5

13. A boiler of the character described comprising a water-backed enclosure including lower and upper portions, said lower portion projecting beyond said upper portion at the rear and enclosing a fire pot and combustion chamber, and said upper portion projecting beyond said lower portion at the front and enclosing flues in communication with said fire pot and combustion chamber through the projecting front portion, a water-backed crown sheet separating said fire pot and combustion chamber from said flues, and a transverse water-backed partition spaced below said crown sheet intermediate said front and rear projecting portions and serving to direct the flow of hot gases and products of combustion over and under said partition through said front projecting portion into said flues. 10 20 25

14. A boiler of the character specified comprising front, back and intermediate sections each having a continuous peripheral water compartment and enclosing a fire pot and combustion chamber, said front section having an upper forwardly-overhanging portion including a rearwardly extending lower wall and forming a burner chamber therebelow, said front section 30 and said intermediate section each having a crown sheet member and a partition member communicatively connected together and to the peripheral water compartments of the sections, and said back section having its upper portions disposed forwardly relative to the lower portion and terminating in a relatively shallow part forming a smoke hood and smoke outlet, said back section having an extended portion on its inner side aligned with the crown sheet members 35 of said intermediate and front sections and forming therewith flues extending from the fire pot and combustion chamber to the smoke outlet. 40 45 50

15. A boiler of the character described comprising a front section, a back section having a smoke outlet therein, and an intermediate transverse section enclosing a fire pot and a combustion chamber, and flues extending from said fire pot and combustion chamber to said smoke outlet, supplemental water ways each including a vertical member formed integrally with and end section of the boiler and horizontal members formed integrally with other of the several boiler sections adjacent the bases thereof and having apertures therein communicating severally with said vertical member and with said boiler sections, a circulating pump connected at its intake side with the return pipe from the heating system, and at its outlet side with the upper end of one of said vertical members, and a hot water heater connected at its outlet side with the upper end of another of said vertical members, and its intake side with the upper part of the boiler. 55 60 65 70
